UNITED STATES PATENT OFFICE.

JULIAN KENNEDY, OF PITTSBURG, PENNSYLVANIA.

FURNACE-VALVE FOR HOT-BLAST STOVES.

SPECIFICATION forming part of Letters Patent No. 593,476, dated November 9, 1897.

Application filed August 15, 1896. Serial No. 602,828. (No model.)

To all whom it may concern:

Be it known that I, JULIAN KENNEDY, of Pittsburgh, in the county of Allegheny and State of Pennsylvania, have invented a new and useful Improvement in Furnace-Valves for Hot-Blast Stoves, of which the following is a full, clear, and exact description, reference being had to the accompanying drawings, forming part of this specification, in which—

5 Figure 1 shows my improved valve in plan view, the valve-casing being in horizontal section. Fig. 2 is a vertical section on the line II II of Fig. 1; and Fig. 3 is an end elevation of the valve, the casing being shown as in 10 section on the line III III of Fig. 1.

15 The valve is principally designed for use in hot-blast stoves.

20 2 is the gas main or flue, in which the valve is inclosed.

25 3 is the valve-seat, consisting of an annular metal casting with hollow rim, through which water may be caused to flow for the purpose of cooling the seat, and the seat is confined between sections of the flue 2 between metal castings 4 5, the casting 5 forming part of the 30 valve-casing.

6 is the valve, composed of a metal disk adapted to slide horizontally to and from the seat 3, the valve-casing extending laterally for that purpose and having an external and 35 removable cap 7. Raised ribs or ridges 8 are formed on the valve-casing to constitute slides upon which the disk may move. For the purpose of moving the disks I employ a rotary shaft 9, which extends vertically through and into the casing and through a stuffing-box 10, which may be packed, so as to prevent the escape of gas. Within the casing this shaft is keyed to the horizontal crank-arm 11,

40 having at the end a connecting rod or link 12, pivoted to a pin or stud 13 at the center of the valve, so that when the shaft 9 is rotated by a suitable lever or handle at the exterior of the casing it will swing the crank-arm 11 radially and will move the valve-disk horizontally, as indicated by full and dotted lines in 45 Fig. 1, the full lines showing the position of the valve when open and the dotted lines showing the same when closed.

50 To prevent upward movement of the valve when closed if blast were inadvertently admitted beneath it, I provide a series of lugs 14, which project inwardly from the casing and serve to hold the valve in place.

55 The stuffing-box 10 is formed at the plane of division between the cap 7 and the body of the valve-casing, so that on removing said cap the stuffing-box will be exposed. The parts are thus rendered easy to assemble, and a gas-tight connection can readily be made. 60 This is a point of substantial advantage.

I claim—

65 In a furnace-valve, the combination with a sliding valve and valve-casing, of a rotatory operating-shaft extending through a stuffing-box into the casing, a crank-arm having a link connection contained within the casing and serving to transmit motion from the shaft to the valve, and a removable cap for said casing, the division-line between the cap and 70 casing extending through the stuffing-box; substantially as described.

In testimony whereof I have hereunto set my hand.

JULIAN KENNEDY.
